UNITED STATES PATENT OFFICE.

GEORGE W. PERKS, OF AKRON, OHIO, ASSIGNOR TO JOHN R. GAMMETER, OF AKRON, OHIO.

COMBINATION GUY AND GUARD.

Application filed May 22, 1926. Serial No. 110,976.

This invention relates to a combination guy and guard for poles, which serve as "telltale" to prevent one from accidentally running into the guy.

5 The chief object of the invention is to provide a guard or telltale which is adapted to form a part of the guy as a tension member, whereby it is positively held in place.

10 The purpose of the invention is to dispense with the usual metal or wooden guard which is secured to guy wires. The guards are expensive and will slip and get out of position upon the wire. The present device obviates these disadvantages by forming 15 the guard as a part of the guy itself, the guard being insulated and under tension and thereby serving as a bracing element in addition to its guarding properties.

15 The foregoing and other objects of the invention are obtained by the construction illustrated in the accompanying drawings and described below. It is to be understood that the invention is not limited to the specific form thereof shown and described.

20 25 Of the accompanying drawings,

Figure 1 is a side elevation, partly in section, of a portion of a guy embodying the invention;

25 30 Figure 2 is a section on line 2—2 thereof; and

Figure 3 is a section on line 3—3 thereof.

Referring to the drawings, 10 represents a guy wire such as commonly used, for example, on telegraph or other poles.

35 40 The numeral 11 indicates an anchor secured in the earth and to which, according to prior practice, the lower end of guy wire 10 is secured.

According to the present invention, the 45 guard, indicated at 12, which may be of any suitable material and formed to any suitable shape, is adapted to be connected to the lower end of wire 10 and to anchor 11 so that it becomes a tension member forming part of the guy. The guard 12 may consist of a metallic shield of U-shape in section to provide spaced parallel legs or members and having aligned sets of bolt apertures 13, 13 in the opposite legs of the U adapted 50 to receive a bolt 14 on which is mounted an insulator 15, about which the lower end of wire 10 may be looped as at 16, insulator 15 having a peripheral groove 15^a therein in which loop 16 may seat. By this arrangement, the effective length of guard 12

is adjustable so that proper tension in guy wire 10 may be obtained.

At its lower end the guard or telltale 12 may have aligned bolt apertures 17, 17 in the opposite legs of the U for receiving 60 a bolt 18 adapted to be inserted through the eye 11^a of anchor 11 to secure the lower end of guard 12 thereto.

It will appear from the foregoing that a simple effective combined guy and guard 65 has been provided for the purpose stated and one which will always be maintained in proper position since it cannot slip along the guy and become distorted. Guards used in the past frequently become a menace instead of a safety device since they slip and are bent so as to present sharp edges likely to cut a person running into the same. This old type of guard on a wire near a curb is also likely to slip so as to project beyond 70 the curb and cut tires of vehicles driven up to the curb.

75 Modifications of the invention may be resorted to without departing from the spirit thereof or the scope of the appended claims. 80

What is claimed is:

1. A guy including a guard or telltale incorporated therein as a tension member, said guy comprising a cable looped at its lower end, an anchor, a guard formed with spaced 85 members with aligned apertures in the members at one end and sets of aligned apertures in the members at the other end, a bolt extending through the apertures at one end and a bolt extending through one set of the 90 apertures at the other end, and an insulator on one bolt, the cable being looped about the insulator and the anchor being connected to the other bolt.

2. A guy including a guard or telltale incorporated therein as a tension member, said guy comprising a cable looped at its lower end, an anchor, a guard formed with spaced members with aligned apertures in the members at each end, a bolt extending through 100 the apertures at each end, and an insulator on one bolt, the cable being looped about the insulator and the anchor being connected to the other bolt.

3. A guy including a guard or telltale incorporated therein as a tension member, said guy comprising a cable looped at its lower end, an anchor, a guard formed with spaced members with aligned apertures in the members at each end, and a bolt extend- 110

ing through the apertures at each end, the cable being secured to one bolt and the anchor to the other bolt.

4. A guy including a guard or telltale incorporated therein as a tension member, said guy comprising a cable looped at its lower end, an anchor, and a guard adapted to have the looped end of the cable secured to one end thereof and the anchor to the other end thereof.

5. A guy including a guard or telltale incorporated therein as a tension member.

6. A guard or telltale for use on guys, said guard having means at each end thereof for securing said guard in the guy as a tension member thereof.

7. A combination guard and guy comprising a wire for attachment to a pole and an anchor in the ground, the device comprising a guard of sufficient size to be visible to 20 form a telltale located between the wire and the anchor and under tension so as to form a part of the guy.

8. A combination guard and guy comprising a wire for attachment to a pole and an anchor in the ground, the device comprising a guard of sufficient size to be visible to form a telltale located between the wire and the anchor and under tension so as to form a part of the guy, and an insulator between 25 the pole and the guard.

GEORGE W. PERKS.
